UNITED STATES PATENT OFFICE.

H. CLAY EVANS AND GEORGE JONES, OF CHATTANOOGA, TENNESSEE.

MAIL-BAG.

SPECIFICATION forming part of Letters Patent No. 291,501, dated January 8, 1884.

Application filed May 22, 1883. (No model.)

To all whom it may concern:

Be it known that we, H. CLAY EVANS and GEORGE JONES, of Chattanooga, in the county of Hamilton and State of Tennessee, have invented a new and useful Improvement in Mail-Bags; and we do hereby declare that the following is a full, clear, concise, and exact description of the construction and operation of the same, reference being had to the annexed drawings, making part of this specification, and to the letters of reference marked thereon.

Figure 1 is a front view of our mail-bag, the mouth being open, ready for filling. Fig. 2 is a vertical cross-section of the same on line *xx*, the mouth being closed, ready for locking.

In the accompanying drawings, A represents the body of the mail-bag, which has secured to it near its mouth a re-enforce piece, C, extending all around the bag, being riveted thereto, the front portion being completely riveted (the re-enforce piece and body of the bag) together by means of the conventional mail-bag rivets; but one or two rows of rivets are used to secure this flap re-enforce piece at and to the back of the bag, the back of the bag and said re-enforce piece being left separate from the lower portion, at which place it is riveted to the bag, (to the top of the said bag,) thereby forming a pocket, F, between the back of the bag and the said re-enforce piece, for a purpose hereinafter stated. This re-enforce piece is extended upward at the back or rear portion, forming a flap, whereas at the front it is cut considerably shorter than the body of the bag. The flap of the re-enforce is preferably made double, for strength and security, the two thicknesses of leather being firmly riveted together; and it is provided with a metal-rimmed elongated eyelet or long slot, E, and secured to the front of the bag A by means of a metallic plate, and passing through the re-enforce piece C is the one staple D. The mouth or top portion, B, of the bag A is adapted to be folded down, the line of fold being just flush with the top of the front portion of the re-enforce piece. When the bag is to be filled, it is opened, as shown in Fig. 1. When it has been filled, the extended top portion or mouth, B, is folded down backward into the pocket before described, and then the extended flap of the re-enforce piece is folded down forward over the said folded-down mouth. The staple

D is passed through the eyelet E, and the lock inserted and locked.

The object of our invention is to render mail-bags more convenient for introducing and removing the mail-matter by those authorized to do so, and more secure against the unauthorized removal of their contents. It is evident that the passage into the properly-closed bag is very tortuous, and that it would be impossible to insert the hand or any instrument into the closed bag, the hand or instrument having to make at least five sharp turns: first under the front of the outer flap on piece C, then over the front of top horizontally, then down at back, then up between the mouth-flaps B B, then finally over the top between these flaps, and then down into the bag, so that meddling with the contents of the bag when closed is absolutely impossible.

But one staple is used in securing our bag, thus saving the expense of many staples and of many metal-faced eyelets, and also saving much valuable time in doing up and undoing the mail-bag. The conventional lacing strap or chain is entirely dispensed with, also dispensing with many staples and the many metallic plates or rivets that commonly surround the eyelets or long staple-slots, thus quite materially reducing both the weight and the cost of mail-bags.

Mail-bags have been made with two flaps, (a front and a back flap,) and these bags have been secured by folding down first one flap, and then the other over this first flap; but such construction is utterly unlike our invention, and we would not suggest it.

Having thus described our invention, we claim as new and desire to secure by Letters Patent of the United States—

1. In a mail-bag, the combination of the extended top of the bag, adapted to be folded down backward into a pocket, and means for securing the same in position, substantially as set forth.

2. In a mail-bag, the combination of the extended top of the bag, adapted to be folded down backward into a pocket formed between the rear side of the bag and the flap, the flap being adapted to be folded down forward over the folded-down top, and means for securing the same in position, substantially as set forth.

3. In a mail-bag, the combination of the

downwardly and backwardly folded top, the pocket formed by the flap and body of the bag, the back flap being provided with an eyelet, and the staple, substantially as described.

5 4. The herein - described mail - bag, constructed with an extended top, a pocket in the rear of the top, an eyeleted flap, and a staple, the extended top being adapted to fold down into the pocket, the flap being adapted to fold 10 down over the folded-down top, the staple to

pass through the eyelet to permit the bag to be locked, as herein described.

In testimony that we claim the above we have hereunto subscribed our names in the presence of two witnesses.

H. CLAY EVANS.
GEORGE JONES.
